UNITED STATES PATENT OFFICE

155,460

DESIGN FOR AN ILLUMINABLE CHRISTMAS DECORATION

Harry G. Sundheim, Jr., Cook County, Ill., assignor to The Glolite Corporation, a corporation of Illinois

Application July 24, 1948, Serial No. 147,743

Term of patent 14 years

(Cl. D26—8)

To all whom it may concern:

Be it known that I, Harry G. Sundheim, Jr., a citizen of the United States, residing at Illinois, county of Cook, and State of Illinois, have invented a new, original, and ornamental Design for an Illuminable Christmas Decoration, of which the following is a specification, reference being had to the accompanying drawing, forming part thereof.

Fig. 1 is a front elevational view of an illuminable Christmas decoration embodying my new design; and

Fig. 2 is a side view of the same.

The back of the article is conventional.

I claim:

The ornamental design for an illuminable Christmas decoration, substantially as shown and described.

HARRY G. SUNDHEIM, JR.
